UNITED STATES PATENT OFFICE.

TURNER D. BOTTOME, OF INDIANAPOLIS, INDIANA.

METHOD OF AND APPARATUS FOR CARBURETING.

1,190,714.

Specification of Letters Patent.

Patented July 11, 1916.

Application filed July 2, 1913. Serial No. 776,920.

To all whom it may concern:

Be it known that I, TURNER D. BOTTOME, a citizen of the United States, residing at Indianapolis, in the county of Marion and State of Indiana, have invented a new and useful Method of and Apparatus for Carbureting, of which the following is a specification.

In carbureting liquid fuels, for the production of explosive mixtures for internal combustion engines, I have found that the carbureting is ordinarily imperfect when the liquid fuel is merely discharged from a nozzle into the air passing such nozzle at low vacuum, as in the ordinary carburetor; and yet this nozzle, by which the fuel is measured, should be near the low vacuum or in-take end of the air passage and between such end and the throttle valve, so that the fuel taken up will vary in proper proportion to the volume of the passing air. This imperfection in carbureting is especially the case when low grade fuels are used, and is due, at least in large part, to the failure to divide the fuel into sufficiently small particles.

It is the object of my invention to increase the fineness of the division of the fuel particles, and in consequence to improve the carbureting of the air and better the explosive mixture. In accomplishing this, the fuel is first discharged from the fuel nozzle in the air passage in the low vacuum part thereof, or between the in-take end and the throttle valve; and this discharged fuel, which at its discharge from the fuel nozzle is preferably divided as finely as possible and mixed with at least part of the air to be carbureted, is conducted at high velocity, together with any air which is mixed with it, to a higher vacuum part of the air passage, or on the high vacuum side of the throttle valve, and there discharged through a vaporizer into such passage and into the remainder, if there is any remainder, of the air to be carbureted. This provides an exceedingly fine division of the fuel and a most intimate mixture of the fuel and the air, the division being much finer than is possible with a single atomization into the low vacuum air.

The accompanying drawing illustrates a simple form of carburetor for carrying out my process.

Figure 1 is a vertical longitudinal section

through such carburetor; and Fig. 2 is a section on the line 2-2 of Fig. 1.

The fuel, which may be contained in a suitable bowl 11, is supplied in any suitable manner to a fuel nozzle 12, which is preferably adjustable, as by a needle valve 13 here shown as operated by a knob 14 below the carburetor, to control the size of the fuel passageway. The fuel nozzle 12 is located in a suitable air passage 15, conveniently supplied through openings 16 at the bottom of the carburetor, which air passage may be contracted somewhat around the discharge end of the nozzle 12. An inverted funnel 16 is located in the passage 15 above the fuel nozzle 12, and is connected by a pipe 17 to a vaporizer 18 farther along in the passage 15, a butterfly throttle valve 30 being located in such passage between the inverted funnel 16 and the vaporizer 18. The fuel nozzle 12 is thus on the low vacuum side of the throttle valve, and the vaporizer 18 is on the high vacuum side thereof. This vaporizer 18 has an upper plate 19 through which are a plurality of openings 20 leading to the space 21 within the vaporizer, and this space 21 is connected to the pipe 17 through an opening adjustable by a needle valve 22 operable in any suitable manner, as by a bevel-gearing 23 actuated by a knob 24. The passage 15 above the vaporizer 18 leads into a pipe 25 connected to the manifold of the engine, and this pipe 25 may be surrounded by a chamber 26 into which hot exhaust gases 90 from the engine may be conducted by a pipe 27, such exhaust gases escaping from such chamber through a pipe 28. A butterfly valve 29 may be located in the pipe 27.

In operation, the suction of the engine 95 produces a current of air through the passage 15 and the pipe 25, part of this air passing at high velocity through the funnel 16, pipe 17, and vaporizer 18 because save when the butterfly valve 19 is wide open 100 there is a very considerably greater vacuum above such butterfly valve and at the discharge of the vaporizer 18 than there is below such butterfly valve and at the nozzle 12. This suction, and the resultant low 105 vacuum around the nozzle 12, picks up fuel from such nozzle in a rather coarse state of division, and mixes it with the air going through the funnel 16, pipe 17, and vaporizer 18. The amount of fuel picked up 110

by the air passing the nozzle 12 increases as the vacuum and consequently the flow of air increases around such nozzle. The state of division here referred to as being rather 5 coarse is the same state of division as that produced in the ordinary commercial carburetor, and while it is coarse as compared with the ultimate state of division, it is what is ordinarily called a fine state of division. 10 The fuel in the mixture of this coarsely divided fuel and part of the air passing through the pipe 17 is much more finely divided when at high velocity such mixture strikes the valve 22 and passes through the 15 vaporizer 18 into the pipe 25, where it mixes with the remainder of air passing upward through the passage 15. The amount of this remainder varies as the throttle valve is adjusted. The fuel is now in a very 20 fine state of division, and in consequence is more intimately mixed with and into the air, thereby producing an explosive mixture which acts more quickly and more powerfully. This intimate mixture of air and fuel 25 in the pipe 25 may be heated by the exhaust gases coming from the engine and passing through the chamber 26, thereby further increasing the power of the explosive mixture by lessening the heat required in the engine to bring it to the kindling temperature and by lessening the opportunity for the 30 fuel to condense in the carbureted air on the sides of the pipe 25. The heat produced in the pipe 25 is communicated by conduction along such pipe to the body of the carburetor, thereby assisting in the atomization at the nozzle 15 and the maintenance of the mixture within the funnel 16, pipe 17, and vaporizer 18.

40 I claim as my invention:

1. The method of carbureting air; which comprises atomizing fuel into a portion of the air to be carbureted, conducting this mixture of the fuel with said portion of the 45 air to an enlarged chamber, and re-atomizing this mixture of air and fuel from such chamber through a contracted orifice into the remainder of the air to be carbureted.

2. The method of carbureting air, which 50 consists in producing suction through an air passage, dividing the flow of air through a portion of such passage into two parts, discharging fuel in a state of division into one of such parts of the air, conducting the resultant mixture of fuel and part of the air to an enlarged chamber and then discharging it from such enlarged chamber through a contracted orifice in a finer state 55 of division into the remainder of the air.

60 3. The method of carbureting air, which comprises discharging fuel into air to be carbureted in a low vacuum part of an air passage, conducting this mixture of air and discharged fuel to an enlarged chamber, and 65 discharging it from said enlarged chamber

through a contracted orifice in a fine state of subdivision into the air passage at a materially higher vacuum part thereof and there mixing it with more air to be carbureted.

70 4. A carburetor, comprising an air passageway, a throttle valve in such passageway, a fuel nozzle in such passageway between the in-take end thereof and such valve, a vaporizer in such passageway between the discharge end thereof and such valve, and means for conducting the fuel discharged from said nozzle and part of the air passing through such passageway to the vaporizer by a path separate from the 75 air passageway, said vaporizer having an enlarged chamber into which said path discharges and a contracted orifice forming a discharge outlet from said enlarged chamber to said passageway, and a vaporizer 80 valve controlling the size of the opening between said path and said chamber.

85 5. A carburetor, comprising an air passageway, a throttle valve in such passageway, a fuel nozzle in such passageway between the in-take end thereof and such valve, a vaporizer in such passageway between the discharge end thereof and such valve, and means for conducting the fuel discharged from said nozzle and part of the 90 air passing through such passageway to the vaporizer by a path separate from the air passageway, said vaporizer having an enlarged chamber into which said path discharges and a contracted orifice forming a discharge outlet from said enlarged chamber to said passageway.

95 6. The method of carbureting air, which comprises discharging fuel into a small portion of the air to be carbureted with such air at comparatively low vacuum, conducting the mixture of air and fuel thus produced to an enlarged chamber, and then discharging such mixture from such chamber through a contracted orifice into the remaining and larger part of the air to be carbureted with such latter air at materially 100 higher vacuum.

105 7. The method of carbureting air, which comprises discharging fuel into a portion of the air to be carbureted with such air at comparatively low vacuum, and discharging the mixture of air and fuel thus produced through a contracted orifice so that its 110 velocity is increased into the remaining part of the air to be carbureted with such latter air at materially higher vacuum.

115 8. The method of carbureting air, which comprises discharging the fuel in a state of subdivision into a portion of the air to be carbureted, conducting this mixture of air and fuel to an enlarged chamber, discharging such mixture from such chamber through a contracted orifice into the remainder of the air to be carbureted, and 120 125 130

throttling the flow of this remainder of the air before it reaches the point where the mixture of fuel with the first part of the air is discharged into it.

5. 9. The method of carbureting air, which consists in producing suction through an air passage, dividing the flow of air through a portion of such passage into two parts, throttling the flow of one of such parts, 10 discharging fuel into the other of such parts, conducting the mixture of fuel with the second part of the air to an enlarged chamber, and discharging such mixture from such enlarged chamber through a contracted orifice into the first part of the air at a point beyond where such first part is throttled.
10. The method of carbureting air, comprising discharging fuel into a small portion of the air to be carbureted, with such air traveling at a low velocity, collecting the stream of mixed air and fuel and conducting it through a passage of reduced size to give increased velocity, discharging it from 15 said passage of reduced size at still higher velocity through a contracted orifice into a chamber wherein the air and fuel are subjected to a violent turbulence and simultaneously allowed to expand, and then immediately discharging such stream of mixed air and fuel from such chamber through an orifice at comparatively high velocity and

finely atomizing it into the main body of air to be carbureted.

11. The method of carbureting air, comprising discharging fuel into a low velocity air stream, collecting the fuel and a small portion of the air stream and conducting such fuel and small portion of air through an ensmalled passage to and atomizing them 40 into a chamber to allow expansion, and then discharging such mixed air and fuel from such chamber through a small orifice in a highly atomized condition into the main body of air to be carbureted. 45

12. The method of carbureting air, comprising discharging fuel into an air stream, throttling the flow of such air stream beyond such fuel discharge, conducting such fuel and a small portion of the air stream 50 through a separate passage into a chamber wherein the fuel and small portion of air are mixed, and then discharging such mixture in a finely atomized condition into the remainder of the air stream at a point beyond where such air stream is throttled. 55

In witness whereof, I have hereunto set my hand at Indianapolis, Indiana, this 30th day of June, A. D. one thousand nine hundred and thirteen.

TURNER D. BOTTOOME.
